EDGAR LANGLEY RANDALL, OF SOUTH HAMPSTEAD, LONDON, ENGLAND, ASSIGNOR OF THREE-FOURTHS TO OLIVER PRESCOTT MACFARLANE, OF LONDON, ENGLAND.

OIL-VAPOR BURNER.

1,195,159.

Specification of Letters Patent. Patented Aug. 15, 1916.

Application filed February 17, 1915. Serial No. 8,823.

To all whom it may concern:

Be it known that I, EDGAR LANGLEY RANDALL, a subject of the King of Great Britain, residing at 11 Lithos road, South Hampstead, N. W., in the county of London, England, have invented certain new and useful Improvements in or Relating to Oil-Vapor Burners, of which the following is a specification.

10 This invention has reference to oil-vapor burners (especially such as used for incandescent lighting with inverted mantles) for use with kerosene or paraffin or other suitable liquid fuel.

15 The main object of the invention is to provide a combination of parts which shall improve the means of vaporization and simplify the mechanical construction of the burner, besides facilitating the keeping 20 clean of the vapor tubes.

The invention is also designed to secure a quick action in starting or lighting up, as well as to reduce the quantity of spirit required for the preliminary heating.

25 A feature of the invention consists in making the parts in which the liquid fuel is converted into vapor, of straight tubes which can thus be freed easily from any carbon or cinder which may form therein, 30 by pushing a wire or rod along them.

Another feature of the invention consists in making the straight vaporizer with a substantially vertical straight portion or tube, forming an auxiliary vaporizer or superheater. This vertical tube depends from 35 the inner end of the horizontal or main vaporizer and reaches the flame of the burner, but does not necessarily pass through the wick pan by which the usual 40 preliminary heating or starting is effected.

The nipple through which the vapor is discharged, is arranged to direct the same upward into a bent-over mixing tube. The said nipple is situated at the junction of the

45 aforesaid vertical tube and the horizontal tube, and is arranged at right angles to the latter. Hence any particles carried along the horizontal tube are not projected directly into the orifice of the nipple, but strike against the side wall thereof, and then drop into the vertical tube or auxiliary vaporizer.

The horizontal main portion or vaporizer tube extends across the underside of a deflector plate, a little to one side of a central

aperture therein, while the air-and-vapor mixing tube passes downward through this aperture to the head of the burner.

The burner proper or burner head is screwed firmly on to a thimble or socket-piece passing through the wick-pan and the mantle carrier, so that these elements form as it were, one single piece ready for attachment to the mixing tube.

In order that the invention may be clearly understood and readily carried into effect, reference will now be had to the accompanying diagrammatic drawings, in which:—

Figure 1 shows mainly in vertical section an example of the improved incandescent 70 burner. Fig. 2 being a plan thereof. Figs. 3, 4 and 5 are detail views hereinafter referred to.

The vaporizer comprises a straight horizontal tube *a* of brass or steel, combined 75 with a vertical tube *b* fixed to one extremity thereof and closed at its bottom end.

The main or horizontal tube *a* is secured (by screwing, by silver solder or otherwise) to a heater tube or filter chamber *c*, 80 which is connected, by a screw-joint at the end *c*¹, with the supply pipe from the reservoir containing the oil or liquid fuel. This oil or fuel is forced into the vaporizer under air-pressure in the manner usual in 85 lamps or burners of this kind.

The heater or filter chamber *c* contains a wire-gauze cartridge or filling through which the oil passes on its way to the vaporizer. The said chamber *c* extends 90 through and is fixed or soldered to the burner shell, cover or inclosure *d*, or to a removable section thereof. Owing to the temperature acquired by the gauze or filling, the tube or chamber *c* serves effectually both 95 as a heater for the incoming oil or fuel, as well as assisting in partly atomizing and vaporizing the latter before it enters the main vaporizer *a*.

The vertical tube *b* is as stated connected 100 to the end of the tube *a*, and the two open into one another. The closed lower end of this vertical tube reaches down to the flame, and is situated just outside the wick-pan *e*, although in some cases it may pass through 105 the latter.

The horizontal vaporizer *a* is placed immediately under a rather thin heat-collecting baffle plate *c*², of brass or other suitable metal. Said baffle is arranged in such a po- 110

sition that the hotter part of the spirit flame from the wick pan plays directly on the same and on the vaporizer when lighting up, thus producing very quick vaporization.

5 The upper end of the vertical tube or auxiliary vaporizer *b*, and the adjacent end of the main tube or vaporizer *a*, are fixed in a hollow junction-piece or block *b*¹ provided with a flange *b*² by which it can be secured 10 by screws or other means, to a flat annular shoulder *d*¹ on the burner cover, shell or enclosure.

*d*² is a contracted portion, neck or funnel on the said cover, through which the products of combustion escape. The said vertical tube *b*, (which is seen partly in section in Fig. 1,) serves to conduct heat to the rest of the vaporizer, while its interior serves as a super-heated well, receptacle or retort, 20 into which any unvaporized oil or solid particles will drop and be instantly vaporized, instead of passing direct to (and choking) the orifice through which the vapor escapes from the vaporizer. That is to say any particles carried along the tube *a*, would strike the opposite wall of the block *b*¹ and fall into the auxiliary vaporizer *b*, instead of being carried into, and choking, the nipple. This nipple is screwed into the hollow junction-piece or connector *b*¹ at the top of the 25 vertical tube *b*. It discharges the vapor upwardly through its orifice *f*¹ (Fig. 5) into the bent-over or arch-shaped end *g*^x of the mixing tube *g* in which the mixture of air and vapor is formed. The necessary quantity of air is drawn in by the suction set up 30 by the vapor jet as it issues under pressure from the orifice *f*¹, on the known principle. The said vapor nipple *f* in the example 35 shown is funnel-shaped, or is coned downwardly, the orifice being at the bottom of the funnel, as seen more clearly in section in Fig. 5. The internal space or recess around the cone-shaped part is intended to 40 receive any carbon or solid particles which might otherwise be carried by the stream of vapor into the orifice *f*¹, as well as any particles that may be pushed down through the orifice in the ordinary pricking or clearing 45 operation.

50 Either an internal or external "pricker" device may be provided for cleaning out the orifice *f*¹ when necessary. It will be seen however that the space between the top of *f* and the mouth *g*⁰ of the mixing tube, is 55 sufficient to allow of the orifice *f*¹ being very easily reached by hand with a needle or pricker from the outside.

60 The mixing tube *g* passes centrally down through the funnel *d*², and the deflector plate or baffle *c*², and is secured (by a screw-joint or otherwise) in a three-armed piece or spider *d*³ fixed in the funnel.

65 The baffle *c*² serves to collect heat from the products of combustion. It may be in

actual metallic contact with the aforesaid filter-tube or heating chamber *c* or be soldered thereto near the upper part thereof, the filter chamber *c* extending nearly up to the central aperture in the deflector, thus 70 securing a comparatively large area of contact and a rapid transmission of heat from the baffle to the filter chamber.

The aforesaid mixing-tube *g* carries at its lower end the wick-pan or spirit cup *e* and 75 burner head *h*, the said pan or cup *e* receiving the spirit for heating the tubes *a*, *b* and *c* at starting.

The burner proper or burner-head *h* is provided with a gauze or perforated plate 80 *h*¹ through which the vapor issues.

The wick-pan or heater *e* shown in section and plan in Figs. 3 and 4 respectively, is directly secured to the burner by a flanged thimble or socket *g*¹ on the tube *g*, which 85 passes through the aperture *e*¹ in the bottom of the pan. The lower end of this socket *g*¹ is screw-threaded below the wick-pan, and the burner-head screws on to it, so that the mantle carrier *g*² is clamped in 90 position between the bottom of the wick-pan and the top edge of the burner-head. The mixing tube *g* fits into the screw-ring *g*¹ and the two are secured together by a split-pin *g*³, or in any convenient way. 95

The burner acts in the ordinary way, the paraffin oil or other liquid fuel being forced under pressure (from a suitable reservoir) 100 through *c*¹ and being partly broken up or atomized by the gauze in the filter-tube or chamber *c*, and partly converted into vapor by the heat of said chamber at the same time. The vaporization is completed in the tubes *a* and *b* and the vapor issues in a fine jet from the nipple *f* with considerable 105 force. The action of the jet draws air into the mouth or inlet *g*⁰ of the mixer tube *g*, the mixture flowing down to the burner-head *h* as indicated by the arrows.

110 The flame issues from *h* and *h*¹, and the products of combustion after leaving the inverted mantle (not shown) carried by *g*², rise up to and escape through the funnel or cover *d* *d*¹ *d*².

115 It will be seen that near the nipple *f* and inlet *g*⁰, the vertical part *d*² of the funnel acts as a partition or separator and prevents any products of combustion finding their way to the inlet *g*⁰ and so deteriorating the mixture.

120 I claim:—

1. In a vapor burner, the combination of a straight horizontal vaporizer tube, a straight filter tube in line therewith and leading directly into the same, a baffle plate 125 secured near the joint of said filter and vaporizer tubes, in metallic contact therewith, an arch-shaped mixing tube the longer limb of which passes down through said baffle plate, and an inverted burner on the lower 130

end of said mixing tube, substantially as described.

2. In a vapor burner for incandescent lighting, the combination of a straight horizontal vaporizer, a filter tube leading into the same, an inverted burner-head below the same, a straight vertical tube or auxiliary vaporizer reaching down to near the burner-head, an inclosing shell forming a funnel and serving to carry the aforesaid parts, and a heat-collecting baffle-plate on the main or horizontal vaporizer tube secured to the said filter tube, substantially as described.
- 10 3. In a vapor burner, the combination of a vaporizer tube, a filter-tube and heater leading into the same, a wick-pan for starting the action, a depending auxiliary heater extending below said wick-pan, a baffle-plate secured to said filter-tube which latter reaches nearly to a central opening in the baffle-plate so as to be heated by the flame and hot gases, an inclosing shell forming a funnel and carrying the aforesaid parts, an

arch-shaped mixing tube extending down 25 through the baffle and carrying the burner head, and means for forcing oil into the burner through the aforesaid filter-tube, substantially as described.

4. In a vapor burner, the combination of 30 a plain straight vaporizer tube, a mixing tube arched over at its upper end, a funnel or casing having a contracted neck outside the top of which lies the mouth of the mixing tube, a burner proper or burner-head 35 screwed on to the lower end of the mixing tube, a flanged thimble or collar arranged above the burner, a wick-pan and mantle-carrier held between said collar and burner-head, and an auxiliary vaporizer extending 40 downward from the main vaporizer beyond the wick-pan, substantially as described.

In testimony whereof I affix my signature in presence of two witnesses.

EDGAR LANGLEY RANDALL.
